UNITED STATES PATENT OFFICE.

HOWARD E. WATKINS, OF NEW YORK, N. Y., ASSIGNOR TO ENOS COMPANY, OF NEW YORK, N. Y., A CORPORATION OF NEW YORK.

DESIGN FOR A BACKPIECE FOR LIGHTING-FIXTURES.

No. 38,144.

Specification for Design.

Patented July 31, 1906.

Application filed May 22, 1906. Serial No. 318,257. Term of patent 7 years.

To all whom it may concern:

Be it known that I, HOWARD E. WATKINS, a citizen of the United States, residing at New York city, in the county of New York and State of New York, have invented a new, original, and ornamental Design for a Backpiece for Lighting-Fixtures, of which the following is a specification, reference being had to the accompanying drawing, forming part thereof.

The figure is a side elevation of a backpiece for lighting-fixtures, showing my new design.

I claim—

The ornamental design for a backpiece for lighting-fixtures as shown.

HOWARD E. WATKINS.
